SELF-PROPELLED LOADER VEHICLE

James J. Bauer, Lisbon, N. Dak., assignor to
Clark Equipment Company

Filed Mar. 31, 1972, Ser. No. 240,344

Term of patent 14 years

Int. Cl. D12—09

U.S. Cl. D40—5 R

FIG. 1

FIG. 2

FIG. 3

FIG. 4

FIG. 5

FIG. 1 is a right side perspective view of a self-propelled loader vehicle showing my new design;
 FIG. 2 is a front perspective view thereof;
 FIG. 3 is a right front perspective view thereof;
 FIG. 4 is a left rear perspective view thereof; and
 FIG. 5 is a rear perspective view thereof.

The undisclosed top is substantially plain and unornamented.

I claim:

The ornamental design for a self-propelled loader vehicle, substantially as shown and described.
